UNITED STATES PATENT OFFICE.

GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC PUSH-SWITCH.

SPECIFICATION forming part of Letters Patent No. 783,911, dated February 28, 1905.

Application filed June 13, 1904. Serial No. 212,340.

To all whom it may concern:

Be it known that I, GEORGE B. THOMAS, a citizen of the United States, residing in Bridgeport, in the county of Fairfield, in the State of Connecticut, have invented Improvements in Electric Push-Switches, of which the following is a specification.

My invention relates to improvements in the construction of that class of electric double push-switches in which the rocking switch-arm carrying the contact-fingers is adapted to be thrown by an inserted key instead of by protruding buttons; and the object of my invention is to so construct such a so-called "lock-switch" that it can always be seen from the face of the switch itself whether the current is on or off and into which of the two key-holes the operating-key must be inserted to throw the switch.

In the accompanying drawings, Figure 1 is a view of the face-plate of the switch. Fig. 2 is a side elevation, partly in section, of the operative parts of the switch. Fig. 3 is a reverse side view of the same. Fig. 4 is a sectional view on the line 4-4, Fig. 2; and Fig. 5 is a cross-section on the line 5-5, Fig. 4.

In push-switches to be operated by keys as usually constructed the two keyholes through which the operating-keys are to be inserted to throw the switch by pressing directly or indirectly upon one end or the other of the switch-lever are formed in the face-plate itself or in fixed escutcheons in the face-plate. In either case it is impossible to tell from the face of the switch whether the current is on or off and into which of the two holes the operating-key must be inserted to throw the switch from its existing position. To meet this difficulty, I combine with the moving part of the switch two followers, which work through openings in the front plate to serve as indicators, but which are so connected to the moving parts of the switch that they cannot be used to operate them. In carrying out my invention I prefer to make these followers out of the escutcheons E and E' for the keys, these escutcheons being in the present instance mounted to slide to a limited extent in and out in

sleeves C C, fixed to the cross-plate B, which carries the frame B' for the switch-lever D. The opposite ends of this switch-lever have pivoted to them rods d d with enlarged heads d' d', guided in the tubular escutcheons E E', which are slotted along one side, as shown at e, Figs. 2, 4, and 5, to permit the escutcheons to slide to a limited extent upon the heads d' d' or to permit the latter to slide within the escutcheons. There is thus provided a "pin-and-slot" or lost-motion connection between the escutcheons and the moving parts of the switch. Normally springs s, carried by the pin s' on the frame B', tend to push these escutcheons inward, Figs. 2 and 3, their inward movement being, however, limited by their coming into contact with stops b' on the frame B', as illustrated at the lower portion of Fig. 2 and upper part of Fig. 3. Either escutcheon is pushed outwardly by the end of the rod d coming against the end of the slot e in the corresponding escutcheon, as shown in the upper part of Fig. 2. Thus when the switch-lever D has been thrown to the closed position, Fig. 2, the face of the escutcheon E will be held about flush with the face of its sleeve C or the face-plate, and at the same time the escutcheon E' will be pressed back within its sleeve C and against the stop b' by the spring s. I prefer to make the face of the escutcheon E of a light color or shade, while the face of the other escutcheon, E', is of a dark color or shade, so that when the escutcheon E is out and the escutcheon E' is in, as shown, it may be seen at once from the face of the switch itself that the current is on and that if it is desired to turn off the current the key must be inserted through the projecting escutcheon E to press on the head d' of the corresponding rod d to throw the switch to the other position. If any one should push on the projected escutcheon with a pencil end, for example, he could not push it far enough to throw the switch because of the stop b'.

Where in the following claims I speak of the face-plate as provided with "keyholes" I use the expression in a sufficiently general sense to apply either to a construction in

which the holes are formed in the metal of the face-plate itself or to a construction such as that specifically shown, in which the heads of the escutcheons form, in effect, a part of the face-plate.

5 I claim as my invention—

1. A double push-switch, having a switch-lever and a face-plate provided with two key-holes for the insertion of a key to actuate the lever and indicating means to indicate into which keyhole the key is to be inserted to operate the switch.
- 10 2. A double push-switch having a switch-lever and a face-plate provided with two key-holes for the insertion of a key to actuate the lever and two indicating-followers connected with lost motion to the switch-lever to indicate the position of the latter, but not capable of operating it.
- 15 3. A double push-switch having a switch-lever and a face-plate with two sliding escutcheons carrying keyholes for the insertion of a key to actuate the lever, the escutcheons be-

ing connected to the switch-lever to indicate the position of the latter.

4. A double push-switch having a switch-lever and a face-plate with two sliding escutcheons for the insertion of a key to actuate the lever, the escutcheons being connected to the lever with a lost motion for the purpose set forth.

5. A double push-switch having a switch-lever and a face-plate with two sliding escutcheons for the insertion of a key to actuate the lever, stops to limit the inward movements of the escutcheons, springs tending to push them inward and a pin-and-slot connection between the escutcheons and moving parts of the switch.

In testimony whereof I have signed my name to this specification in the presence of two subscribing witnesses.

GEORGE B. THOMAS.
